(57) **CLAIM**

I claim the ornamental design for a bicycle passenger peg, as shown and described.

DESCRIPTION

FIG. 1 is a perspective view of the bicycle passenger peg according to the invention;

FIG. 2 is a bottom view of the bicycle passenger peg as shown in FIG. 1; and,

FIG. 3 is a side elevational view of the bicycle passenger peg as shown in FIG. 1.

1 Claim, 3 Drawing Sheets

FIG. 1

FIG. 2

FIG. 3
